UNITED STATES PATENT OFFICE.

WALTER B. MEHL, OF NEWTON, MASSACHUSETTS, ASSIGNOR TO THE KEYSTONE WATCH CASE COMPANY, OF PHILADELPHIA, PENNSYLVANIA, A CORPORATION OF PENNSYLVANIA.

WATCH-MOVEMENT.

977,320.

Specification of Letters Patent. Patented Nov. 29, 1910.

Application filed April 14, 1910. Serial No. 555,401.

To all whom it may concern:

Be it known that I, WALTER B. MEHL, a citizen of the United States, and a resident of Newton, in the county of Middlesex and 5 State of Massachusetts, have invented certain new and useful Improvements in Watch-Movements, of which the following is a specification.

This invention relates to those parts of a 10 stem winding and setting watch movement which support and provide the necessary bearings for the winding stem and certain adjacent parts, my improvements being particularly designed for use in connection with 15 the "American" type of watch movement, so-called, and being intended to improve upon prior constructions in certain particulars which will hereinafter appear.

In the accompanying drawings: Figure 20 1 illustrates a portion of a watch movement containing my improvements as preferably constructed, and shows the parts as viewed from the front or dial side thereof; Fig. 2 is a plan view of the same parts as viewed 25 from the rear or inner side of the dial plate; Fig. 3 is a central longitudinal section through the winding stem and connected parts; Fig. 4 is a plan view of a supporting piece hereinafter described; and 30 Figs. 5 and 6 are side and end elevations of the same respectively.

Referring to the drawings, that portion of the winding stem 2 which is contained within the watch case comprises, as usual, a 35 squared portion 3 on which the clutch 4 slides, a cylindrical portion 5 on which the winding pinion 6 is mounted to turn, and a cylindrical bearing portion 7 formed at the inner end of the stem. The bearing for 40 the portion 7 is formed within the inner end portion 8 of a supporting piece 9 which by preference is substantially yoke-shaped as shown in Figs. 4, 5 and 6, and recessed at its outer end, as at 10, to receive the adjacent portion of the winding stem. This 45 recess 10 is preferably made large enough to receive the winding stem loosely, as the bearing for the outer portion of said stem is provided by the rim portion of the watch 50 case, provision being thus made for fitting the winding stem to the bearings at its inner and outer portions regardless of any slight inaccuracy in the adjustment of the watch movement with respect to the rim 55 portion of the watch case. The supporting

piece 9 is secured to the back side of the dial plate 11 as by screws 12, Figs. 1 and 2, and the space between its end portions overlies and coincides substantially with an opening 13 cut in the dial plate, whereby a 60 space is provided within which the clutch 4 is adapted to be slid longitudinally by the usual setting lever (not shown) when the parts are shifted from winding to setting position and vice versa. As thus constructed, 65 the winding stem with the clutch and winding pinion located thereon can be inserted at its inner end into the bearing provided therefor by the supporting piece 9 and then attached to the dial plate by securing the 70 supporting piece thereto, whereupon these parts will be permanently held in assembled relation without danger of being separated or thrown out of adjustment in any way by combining them with the other 75 parts of the watch movement. The assembling and testing of the parts are thereby greatly facilitated, particularly as compared with those prior constructions in which the bearing for the inner end of the 80 winding stem has been formed in part on a portion of the barrel bridge, in which case the removal of the barrel bridge has necessarily resulted in leaving the inner end of the winding stem loose and therefore likely 85 to be moved out of its intended position.

In addition to the construction above described, my invention also includes an arrangement whereby the part in which the bearing for the inner end of the winding 90 stem is formed, namely, the portion 8 of the supporting piece 9 in the particular construction illustrated, is also utilized to carry the bearing on which the setting wheel 14 is mounted, said bearing consisting of a cylindrical stud 15 formed on the front or outer side of said portion 8 and extending through the dial plate 11. Said stud 15 has a shoulder 16 at its base, whereby the setting wheel 95 is held at the proper distance from the winding stem, and the setting wheel is held in place on the stud 15 by suitable means such as a cap piece 17, which is located on the front or outer side of the dial plate and is secured thereto by a screw 18, as shown in 100 Figs. 1 and 3. A pin 19 passing from the cap piece 17 into the dial plate 11 prevents said cap piece from turning on its attaching screw, and that end of said cap piece which 105 overlies the setting wheel 14 is preferably 110

provided with a laterally-extending projection 20 so located as to overlie the minute wheel 21 and thereby prevent the latter from slipping off the stud on which it is journaled. 5 The parts just described are so proportioned and arranged that when they are assembled and the supporting piece 9 is secured in place, the setting wheel 14 meshes with the minute wheel 21 and is also in position to be 10 engaged by the clutch 4 when the latter is moved into setting position.

Heretofore it has been customary to provide independent supports for the setting wheel and the inner end of the winding stem, 15 and in order to do this it has been necessary either to insert a short shouldered stud into the dial plate for the purpose of receiving and providing the bearing for the setting wheel, or else to form this bearing integral 20 with the dial plate. In the former case the bearing for the setting wheel has been unavoidably weak and extremely liable to breakage or displacement, while in the latter case it has been necessary to employ a dial 25 plate of considerable thickness, relatively speaking, whereas with my construction a strong and stable bearing is provided for the setting wheel, independently of the dial plate, so that the latter be made as thin as desired. This feature of my invention is 30 therefore particularly applicable to watches of that type in which the dial plate is made thin and is combined with a false plate, so called, it being possible with my construction 35 to form each of these plates, with the necessary perforations and recesses therein, by a simple punching operation.

The complete construction above described also has the advantage that not only the 40 winding stem but also the setting wheel may be permanently attached to the dial plate in adjusted position, independently of any of the other parts of the movement, so that the entire setting mechanism may be readily assembled and tested while exposed to view 45 and without reference to any other part or mechanism. This and other advantages will be readily apparent without further description, and it will also be apparent that the details of construction of the several parts may 50 be variously modified without departing from my invention.

I claim as my invention:

1. In a watch movement of the type in 55 which the outer end of the winding stem is adapted to be journaled in the watch case, the combination of the winding stem having a winding pinion and a sliding clutch thereon, a dial plate recessed to receive said

pinion and clutch, and a yoke-shaped supporting piece secured to the dial plate and provided at its inner end with a bearing in which the inner end of the winding stem is mounted, said supporting piece being provided at its outer end with a recess adapted to receive the adjacent portion of the winding stem with sufficient looseness to permit a slight lateral displacement of the stem within the said recess when the outer portion of said stem is fitted within its bearing 60 in the watch case. 65

2. In a watch movement of the character described, the combination with the dial plate and winding stem, of a supporting piece secured to the rear face of said dial plate and provided with a bearing for the inner end of the winding stem, said supporting piece being also provided with a cylindrical stud passing through the dial plate and projecting on the front side thereof, and a setting wheel journaled on said stud in front of the dial plate. 75 80

3. In a watch movement of the character described, the combination with the dial plate and winding stem, of a supporting piece secured to the rear face of said dial plate and provided with a bearing for the inner end of the winding stem, said supporting piece being also provided with a cylindrical stud passing through the dial plate and projecting on the front side thereof, a setting wheel journaled on said stud in front of the dial plate, and a cap piece secured to the dial plate and covering the outer end of said stud. 90 95

4. In a watch movement of the character described, the combination with the dial plate and winding stem, of a supporting piece secured to the rear face of said dial plate and provided with a bearing for the inner end of the winding stem, said supporting piece being also provided with a cylindrical stud passing through the dial plate and projecting on the front side thereof, a setting wheel journaled on said stud in front of the dial plate, and a cap piece secured to the dial plate and covering the outer end of said stud. 100 105 110

In testimony whereof, I have hereunto subscribed my name this 12th day of April, 1910.

WALTER B. MEHL.
